UNITED STATES PATENT OFFICE

JESSE A. B. SMITH, OF STAMFORD, CONNECTICUT, ASSIGNOR TO UNDERWOOD ELLIOTT
FISHER COMPANY, OF NEW YORK, N. Y., A CORPORATION OF DELAWARE

TYPEWRITING MACHINE

Application filed June 25, 1928. Serial No. 287,935.

This invention relates to typewriting machines and more particularly to means for providing an opening or gap between the platen and the front of the paper-table, sufficiently large to facilitate front insertion of a pack of work-sheets.

For obtaining a front-insertion opening, means have heretofore been provided whereby the bottom paper-apron was slidden down away from the platen at the paper-releasing operation, or the paper-table was mounted to be rocked during the paper-release, in order to swing the front portion of the apron away from the platen.

Since in standard typewriting machines the extent to which the paper-table can normally be displaced is limited by the presence of mechanism below and in front of the platen, the use of the old devices has given only a limited sheet-inserting opening which was found not to accommodate a large number of work-sheets and carbons.

A feature of the present invention is the provision of means whereby the paper-apron of a standard Underwood machine can be spaced from the platen sufficiently to permit easy insertion of a pack of sheets and their carbons, with a minimum of alterations to the machine.

For this purpose the paper-apron is slidable automatically downward away from the platen upon the release of the feed-rolls; and said apron is further provided at its front with an extension which is so mounted that simultaneously with its aforesaid downward movement there is imparted to it a swinging movement, in order to carry the forward portion thereof a further distance away from the platen, and thereby provide an ample sheet-inserting gap.

The paper-table has at each side downwardly-extending hooks straddling the feed-roll rock-shaft, upon which means is mounted to engage said hooks and move the paper-apron down away from the platen during the releasing of the feed-rolls.

The extension is pivotally supported on the front feed-roll-shaft and it is provided with a projection that normally engages a fixed abutment, which is so arranged that

during the downward movement of the extension with the feed-rolls and paper-table the abutment will be effective to swing the extension about its pivots, causing the front portion of the extension to be moved further away from the platen. 55

The front wing-scale also has its upper portion bent outwardly and arranged to cooperate with the front of the auxiliary paper-apron to form a further extension thereof. The platen is shifted to its upper-case position, and then the feed-rolls, together with the paper-table and its extension, are released. The displacement of the auxiliary apron causes it to engage and swing the wing-scale away from the platen to a position where the top of the scale directly underlies the top of the usual ribbon-spool, so as to produce a maximum sheet-inserting mouth fully equal to the distance between the ribbon-spool and the platen, thus enabling an unusually thick pack of sheets to be readily inserted at the front of the machine. 60 65 70

Other features and advantages will hereinafter appear. 75

In the accompanying drawings,

Figure 1 is a side view, in elevation, showing a portion of a typewriting machine with the carriage shifted to its upper-case position and the feed-rolls and the paper-table 80 moved away from the platen for the insertion of a pack of sheets.

Figure 2 is a perspective view of a part of a typewriter-carriage, to clearly show the feed-roll mechanism together with the construction of my invention. 85

Figure 3 is a view similar to Figure 1 with the carriage in its upper-case position and the feed-rolls and the paper-table in their 90 normal effective positions.

Figure 4 is a view similar to Figure 3, but showing the carriage in its lower-case position.

Figure 5 is a front view, in elevation, showing a portion of a typewriting machine with the carriage moved to its extreme right for sheet inserting, and parts of the machine being broken away or omitted to show the invention more clearly. 95 100

Figure 6 is a fragmentary plan view of the structure shown in Figure 5.

Figure 7 is a diagrammatic view of parts shown in Figure 1, but showing a pack of sheets being inserted with the wing-scale omitted and the platen in its lower-case position.

In an Underwood typewriting machine, types 10 strike against a platen 11 mounted in end plates 12 of a platen-frame 13 supported in a carriage-frame 14, slidably mounted on a stationary main frame 15. The end plates 12 of the platen-frame are connected by an upper cross-bar 16 and a lower cross-rod 17.

The platen-frame may be shifted to an upper-case typing position by a shift-key-lever 18 rocking a shift-frame 19, which, through its engagement with a roller 20 on the platen-frame, moves the latter vertically upward.

The platen-frame is guided in its vertical movement by the usual guide-arms 21.

Front and rear feed-rolls 22 are mounted on shafts 24 and 25, respectively, journaled in arms 26 of bell-crank 27 rotatably mounted on the cross-shaft 17. Depending arms 28 of said bell-crank are disposed on opposite sides of a rock-shaft 29, journaled in depending hanger members 30 fixed to the cross-shaft 17.

The rock-shaft 29 has cutouts 31 on its front and rear sides forming flat portions for engagement with the depending arms 28, to cam the arms 28 outwardly and swing the feed-rolls downwardly against the tension of pressure-springs 23, upon rotation of the shaft 29 caused by the operation of a release lever 32 pivotally mounted on one of the end plates 12 of the platen-frame 13 and connected to the rock-shaft 29 by a link 33. The rock-shaft 29 is prevented from horizontal movement by pins 34 fixed thereto and extending through slots 35 in the hanger members 30.

A paper-table 36, extending downwardly and forwardly and having its lower portion curved under and around the platen, is slidably mounted on the cross-bar 16 by means of a pair of slots 37, through which screws 38 project, and are threaded into the cross-bar 16. The paper-table is held in its normal position in close proximity to the platen, by means of springs 39, at the rear of the paper-table. The springs are connected at one end to said screws 38 and at their other end to pins 40 fixed on said paper-table.

The operation of the feed-roll-release-lever 32 when releasing the feed-rolls actuates means to simultaneously slide the paper-table 36 downwardly and forwardly, to provide a front-sheet-insertion opening between the table and platen. Said means includes a pair of downwardly-extending hooks 41 fixed to the paper-table 36, one at each side thereof, and having their lower ends or curved portions 42 straddling the rock-shaft 29 to guide

them together with the paper-table in a fixed course during their sliding movement away from and towards the platen.

Each curved portion 42 is provided with a projection 43 extending into the path of a flat portion 44 of a collar 45 rigidly mounted on the rock-shaft 29, to rotate therewith when the latter is operated to release the feed-rolls. The flat portions 44, during their rotation, engage the projections 43 and pull the hooks down, which, in turn, slide the paper-table down with them, thus creating a space between the platen and table.

The space, although limited by the mechanism below the platen, is probably sufficient to permit easy front insertion of a single sheet, but when desired to front insert several sheets in the form of a pack, difficulty is encountered in threading all the bottom edges of the pack into said opening.

In order to overcome this difficulty an auxiliary table 46 is provided, which forms an extension at the front of the paper-table 36. Said extension is swingably mounted through brackets 47, being fixed to said extension, and rotatably supported at the ends of the front feed-roll-shaft 24. The paper-table and the extension are provided with interleaved curved fingers 48 and 49, respectively. The fingers are so arranged as to always form a smooth surface between the table and the extension regardless of their positions, so that the leading edges of the paper may pass freely and uninterruptedly from one table to the other during the insertion of the sheets.

The brackets 47 of the extension 46 are each provided with a projection 50 lying in the path of a stationary abutment 51 fixed to the cross-shaft 17, so that during the movement of the paper-table and feed-rolls away from the platen, the auxiliary paper-table, being mounted on the front feed-roll-shaft, is also swung away from the platen, and since the projections 50 are in contact with the fixed stationary abutments 51 during the auxiliary paper-table's downward movement with the feed-rolls, the brackets and extension will be rotated about the feed-roll-shaft 24 against the tension of returning springs 52 attached at one end to the extension 46, and at the other ends to pins 53 fast on the stationary hanger members 30.

By this means the front of the extension is swung down, away from the platen, with the feed-rolls, and also swung further away from the platen through its rotation about the feed-roll-shaft, caused by the fixed abutments 51 acting on the projections 50. It can readily be seen that in this manner a large opening is provided between the platen and the front of the auxiliary paper-table, to facilitate the front insertion or threading of a pack of sheets 63 into said opening.

A wing-scale 54 may be employed to cooperate with the paper-table 36 and its exten-

sion 46, in forming an extremely large sheet inserting opening in front of the platen. The scale 54 is swingably supported in brackets 55 and 56. The bracket 55 is mounted on a type-bar segment 57, while the bracket 56 is supported by a second bracket 58 fixed to the main frame 15. The scale 54 extends outwardly from the right of a type-bar guide 59 a distance substantially the same as the length of the platen, so as to co-operate with its entire length when the carriage is moved to the right for sheet inserting (see Figure 5). The scale 54 is normally pressed towards the platen by springs 60. When it is desired to front insert a pack of sheets 63 into the machine, the carriage is first returned to its extreme right and the platen shifted and locked in its upper-case position, where it can be left until the beginning of typing, which usually starts with a capital letter.

The shifting of the platen at this time raises the platen-frame up and brings the front of the auxiliary table closer to the top of the shiftless parts in the front of the platen, including a ribbon-spool 61, which is mounted closely adjacent the front of the platen. The platen shifting also positions the auxiliary table to co-operate with an outwardly-extending flange 62 of the wing-scale 54, so that when the feed-rolls, paper-table and auxiliary paper-table are moved down away from the platen, the last-mentioned paper-table will engage the wing-scale and swing it forwardly away from the platen, against the tension of said springs 60 (see Figure 1).

In this position the flange 62 forms a continuation of the auxiliary table 46, which terminates at the edge of the ribbon-spool 61. The pack of sheets 63 may now be inserted in the space between the ribbon-spool and the platen and guided down underneath and around to the rear of the platen by means of the flange 62, the auxiliary table 46 and the regular paper-table 36.

The sheets may then be positioned in the machine, and the rock-shaft rotated through the lever 32 to return the feed-rolls to their normal effective position and simultaneously return the auxiliary table and wing-scale by means of their springs 52 and 60, respectively. The rotation of the shaft 29 moves the flat portion 44 away from the projection 43 and permits the paper-table through the springs 39 to be pulled up to its position close to the platen, at which time the sheets may be typed.

Variations may be resorted to within the scope of the invention, and portions of the improvements may be used without others.

Having thus described my invention, I claim:

1. In a typewriting machine, the combination with a platen-frame, a revoluble platen in said frame, lower feed-rolls engaging against said platen and a feed-roll re-

lease-lever, of a rear paper-table slidably mounted on said platen-frame and extending downwardly and forwardly around said platen closely adjacent thereto, an extension adjacent the front of said paper-table and mounted independently thereof, and means additional to said paper-table and extension, to simultaneously displace both said paper-table and said extension in the same direction away from the platen during the releasing movement of said feed-rolls.

2. In a typewriting machine, the combination with a platen-frame, a revoluble platen in said frame, lower feed-rolls engaging against said platen and a feed-roll release-lever, of a rear paper-table slidably mounted on said platen-frame and extending downwardly and forwardly around said platen closely adjacent thereto, means co-operating with the slideable mounting of said table for guiding it forwardly and downwardly along a fixed course to space it from the platen, an extension at the front of said table, and means, additional to said paper-table and extension, to simultaneously slide said paper-table and extension downwardly and forwardly and swing said extension away from the platen during the releasing operation of the feed-rolls to provide a sheet-inserting opening between the platen and paper-tables.

3. In a typewriting machine, the combination with a platen-frame, a revoluble platen in said frame, lower feed-rolls engaging against said platen and a feed-roll release-lever, of a rear paper-table slidably mounted on said platen-frame and extending downwardly and forwardly around said platen closely adjacent thereto, means co-operating with the slideable mounting of said table for guiding it forwardly and downwardly along a fixed course to space it from the platen, an auxiliary table forming a continuation of said paper-table and movable forwardly and downwardly with the latter, means to move said tables simultaneously with the releasing operation of the feed-rolls, and means effective during said movement to swing said auxiliary table about its pivot-bearings to provide a wide sheet-inserting opening at the front of the platen.

4. In a typewriting machine, the combination with a platen-frame, a revoluble platen in said frame, lower front and rear shafts holding feed-rolls against said platen and a feed-roll release rock-shaft, of a rear paper-table slidably mounted on said platen-frame and extending downwardly and forwardly around said platen closely adjacent thereto, means co-operating with the slideable mounting of said table for guiding it along a fixed course to space it from the platen, a paper-table extension swingably mounted on the front feed-roll shaft, and means for moving the paper-table, the extension and the feed-

rolls away from the platen upon operation of said rock-shaft.

5. In a typewriting machine, the combination with a platen-frame, a revoluble platen in said frame, lower front and rear shafts holding feed-rolls against said platen and a feed-roll release rock-shaft, of a rear paper-table slidably mounted on said platen-frame and extending downwardly and forwardly 10 around said platen closely adjacent thereto, means co-operating with the slidable mounting of said table to displace and guide it from the platen, a paper-table extension swingably mounted on the front feed-roll 15 shaft and movable away from the platen with said feed-rolls, and a projection on said extension engaging a fixed abutment in said platen-frame to swing said extension about its bearings during its movement away from the 20 platen with the feed-rolls thereby displacing the forward portion of said extension a still greater distance away from said platen and providing a wide opening between the platen and the paper-table for the front insertion of a pack of sheets.

6. In a typewriting machine, the combination with a platen-frame, a revoluble platen in said frame, lower feed-rolls engaging against said platen and a feed-roll release-lever, of a rear paper-table slidably mounted on said platen-frame and extending downwardly and forwardly around said platen closely adjacent thereto, means to displace and guide said table forwardly and downwardly from the platen, a separate pivoted auxiliary table mounted in line with and forming an extension at the front of said paper-table, and means operating simultaneously with said paper-table displacing 40 means to move said extension downwardly and forwardly and swing the same away from the platen.

7. In a typewriting machine, the combination with a platen-frame, a revoluble platen in said frame, lower feed-rolls engaging against said platen and feed-roll releasing mechanism, of a rear paper-table slidably mounted on said platen-frame and extending downwardly and forwardly around said platen closely adjacent thereto, means to displace and guide said table forwardly and downwardly from the platen during the releasing operation of said feed-rolls, a separate pivoted auxiliary table mounted in line with and forming an extension at the front of said paper-table, and means operating simultaneously with said paper-table displacing means and controlled by said feed-roll mechanism to swing said extension away 60 from the platen.

8. In a typewriting machine, in combination, a platen-frame, a platen revoluble in said frame, a shaft holding lower front and rear feed-rolls against said platen, a rear paper-table slidably mounted in said platen-

frame, an extension at the front of said paper-table and swingably mounted on said front feed-roll shaft, a rock-shaft for releasing said feed-roll, and means operable by said rock-shaft during the feed-roll releasing operation to displace said paper-table and extension away from the platen.

9. In a typewriting machine, in combination, a platen-frame, a platen revoluble in said frame, a shaft holding lower front and rear feed-rolls against said platen, a rear paper-table slidably mounted in said platen-frame, and extension at the front of said paper-table and swingably mounted on said front feed-roll shaft, a rock-shaft for releasing said feed-roll, and means operable by said rock-shaft during the feed-roll releasing operation to slide said paper-table forwardly and downwardly away from the platen and simultaneously swing said extension away from the platen to provide a gap for facilitating the front insertion of a pack of worksheets.

10. In a typewriting machine, in combination, a platen-frame, a revoluble platen in said frame, lower front and rear shafts carrying feed-rolls, a cross-rod, arms pivoted on said rod and supporting the feed-roll shafts, a rock-shaft for swinging said arms on said cross-rod to move said feed-rolls toward and away from the platen, a rear paper-table mounted in said platen-frame and extending downwardly and forwardly around said platen, a separate pivoted auxiliary paper-table mounted in line with and forming an extension at the front of said paper-table and mounted for pivotal movement on said front feed-roll shaft, and means to rock the auxiliary paper-table toward and away from said platen with said feed-rolls.

11. In a typewriting machine, in combination, a platen-frame, a revoluble platen in said frame, lower front and rear shafts carrying feed-rolls, a cross-rod, arms pivoted on said rod and supporting the feed-roll shafts, a rock-shaft for swinging said arms on said cross-rod to move said feed-rolls toward and away from the platen, a rear paper-table slidably mounted in said platen-frame and extending downwardly and forwardly around said platen, means for automatically sliding said paper-table away from said platen during the releasing of the feed-rolls, and an extension at the front of said paper-table and mounted on said front feed-roll shaft to move toward and away from said platen with said feed-rolls.

12. In a typewriting machine, in combination, a platen-frame, a revoluble platen in said frame, platen-shifting mechanism for raising said platen to an upper-case typing position, lower front and rear shafts carrying feed-rolls, a cross-rod, arms pivoted on said cross-rod and supporting said feed-roll shafts, a rock-shaft for swinging said arms 125

on said cross-rod to move said feed-rolls toward and away from the platen, a rear paper-table mounted in said platen-frame and extending downwardly and forwardly

5 around said platen, an auxiliary paper-table at the front of said table and mounted on said feed-roll shafts to move toward and away from the platen with said feed-rolls, a pivoted wing-scale at the front of the platen, 10 and a flange on said wing-scale to form a continuation of said auxiliary paper-table when said platen-frame is in its upper-case position and said paper-tables displaced.

13. In a typewriting machine, in combination, a platen-frame, a revolute platen in said frame, platen-shifting mechanism for raising said platen to an upper-case typing position, lower front and rear shafts carrying feed-rolls, a cross-rod, arms pivoted on said cross-rod and supporting said feed-roll shafts, a rock-shaft for swinging said arms on said cross-rod to move said feed-rolls toward and away from the platen, a rear paper-table mounted for displacement in said platen-frame and extending downwardly and forwardly around said platen, an auxiliary paper-table at the front of said table and mounted on said feed-roll shaft to move toward and away from the platen with said feed-rolls, a pivoted wing-scale at the front of the platen, a flange on said wing-scale to form a continuation of said auxiliary paper-table when said platen-frame is in its upper-case position and said paper-tables displaced, 35 and means to move said scale toward and away from said platen with said paper-tables.

14. In a typewriting machine, the combination with a platen-frame, a revolute platen mounted in said frame, lower feed-rolls bearing against said platen and a feed-roll releasing mechanism, of paper-deflecting means, including a rear paper-table extending downwardly and forwardly around said platen and an auxiliary paper-table independent of the rear paper-table adjacent the front of said rear paper-table, and means operable during the releasing of said feed-rolls to move said paper-table and extension downwardly and forwardly away from the 45 platen to provide an opening for the front insertion of a pack of sheets.

15. In a typewriting machine, the combination with a platen-frame, a revolute platen mounted in said frame, lower feed-rolls bearing against said platen and a feed-roll releasing mechanism, of paper-deflecting means, including a rear paper-table slidably mounted on said platen-frame and extending downwardly and forwardly around said platen, an auxiliary paper-table adjacent the front of said rear paper-table, a wing-scale having its upper end flared outwardly to cooperate with said auxiliary paper-table to form a continuation thereof, and means operable during the releasing of said feed-rolls

to move said paper-table, extension and wing-scale away from the platen to provide an increased front opening for the insertion of a pack of sheets.

16. In a typewriting machine, in combination, a platen-frame, a revolute platen in said frame, lower front and rear shafts carrying feed-rolls, a cross-rod, arms pivoted on said rod and supporting the feed-roll shafts, a rock-shaft for swinging said arms on said cross-rod to move said feed-rolls toward and away from the platen, a rear paper-table slidably mounted in said platen-frame and extending downwardly and forwardly around said platen, means for automatically 70 sliding said paper-table away from said platen during the releasing of the feed-rolls, an extension at the front of said paper-table, brackets fixed to said extension and swingably mounted on said front feed-roll shaft 75 to move toward and away from said platen with said feed-rolls, and projections on said brackets engaging fixed abutments to swing said extension about said feed-roll shaft during the movement of said feed-rolls to provide an enlarged opening at the front of the platen for the insertion of a pack of sheets.

17. In a typewriting machine, in combination, a platen-frame, a revolute platen in said frame, lower front and rear shafts carrying feed-rolls, a cross-rod, arms pivoted on said rod and supporting the feed-roll shafts, a rock-shaft for swinging said arms on said cross-rod to move said feed-rolls toward and away from the platen, a rear paper-table slidably mounted in said platen-frame and extending downwardly and forwardly around said platen, means for automatically 90 sliding said paper-table away from said platen during the releasing of the feed-rolls, an extension at the front of said paper-table, brackets fixed to said extension and swingably mounted on said front feed-roll shaft 95 to move toward and away from said platen with said feed-rolls, projections on said brackets engaging fixed abutments to swing said extension about said feed-roll shaft during the movement of said feed-rolls, and means at the front of said extension to cooperate therewith in forming a further continuation of said extension when displaced from the platen to provide an enlarged opening at the front of the platen for the insertion of a pack of sheets.

18. In a typewriting machine, in combination, a platen-frame, a revolute platen in said frame, lower front and rear shafts carrying feed-rolls, a cross-rod, arms pivoted on said rod and supporting the feed-roll shafts, a rock-shaft for swinging said arms on said cross-rod to move said feed-rolls toward and away from the platen, a rear paper-table slidably mounted in said platen-frame and extending downwardly and forwardly around said platen, means for automatically 120

- sliding said paper-table away from said platen during the releasing of the feed-rolls, an extension at the front of said paper-table, brackets fixed to said extension and 5 swingably mounted on said front feed-roll shaft to move toward and away from said platen with said feed-rolls, projections on said brackets engaging fixed abutments to swing said extension about said feed-roll shaft during the movement of said feed-rolls, and means at the front of said extension to co-operate therewith in forming a further continuation of said extension when displaced from the platen to provide an enlarged opening 10 at the front of the platen for the insertion of a pack of sheets, said means including a swingable wing-scale having its upper end flared outwardly and swingable away from the platen by said extension.
20. 19. In a typewriting machine, the combination with a platen-frame, a revoluble platen in said frame, a rear paper-table, lower front and rear shafts, feed-rolls held thereby against said platen, and a feed-roll-release 25 rock-shaft, of a paper-deflector pivoted by and swingable on the front feed-roll shaft, and means for moving the paper-deflector and the feed-rolls away from the platen upon operation of said rock-shaft.
30. 20. In a typewriting machine, the combination with a platen-frame, a revoluble platen in said frame, a rear paper-table, lower front and rear shafts, feed-rolls held thereby against said platen, and a feed-roll- 35 release rock-shaft, of a paper-deflector forming a continuation of the upper surface of said table, said deflector being solely supported by said front feed-roll shaft, pivoted by and swingable on the front feed-roll shaft, 40 and means for moving the paper-deflector and the feed-rolls away from the platen upon operation of said rock-shaft.
